UNITED STATES PATENT OFFICE

WILLIAM O. MICHELSSEN, OF WOODHAVEN, NEW YORK, ASSIGNOR TO ROYAL TYPE-WRITER COMPANY, INC., OF NEW YORK, N. Y., A CORPORATION OF NEW YORK

TYPEWRITING MACHINE

Application filed December 27, 1927. Serial No. 242,689.

This invention relates to a type action particularly adapted for power driven machines in which there are a plurality of sliding type bars which converge to a common printing center and wherein each type bar is provided with a plurality of groups of two type each. Each type bar is operated by two key levers which are adapted to select corresponding types of each group while the platen is shifted in the usual or any desired manner to bring it into a position to cooperate with one or the other of the type of each group.

The sliding type bars are actuated by a toggle mechanism which reaches a substantially straight line position at the time of printing so that the actual printing is performed by pressure rather than by impact. Means are provided for obtaining a relative adjustment between the normal position of the platen and the type bars in order that the force of the imprint may be varied as desired for manifolding.

One of each pair of keys merely gives the type bar a sliding movement, while the other key in addition gives a lifting movement to a guide member which supports the type bar in its travel to the printing point, thereby lifting the bar into position to print from the corresponding type of the other group.

The invention also comprises specific power operated mechanism for actuating the type bars by which either or both of the above described movements are given to the operated type bar. In many respects this invention is to be regarded as an improvement upon the construction shown in my application Serial No. 227,997 filed Oct. 22, 1927.

Further details of the invention will be apparent from the following description and set forth in the appended claims.

In the drawings:

Figure 1 is a side elevation of a single type action with parts in fore and aft section with the parts in normal position.

Figure 2 is a similar view showing the parts in operated position and adapted to print from the other group of type.

Figure 3 is a sectional view of a modification of mechanism for limiting the shifting movement of the type bar guide member.

Figure 4 is a side elevation of a portion of the power actuated mechanism showing the parts in full lines at the end of a depression of a key and certain parts in dotted lines at a later point in the operation of the device. 53

Figure 5 is a similar view showing in full lines parts in a position subsequent to the dotted line position of Figure 4 and in dotted lines certain parts during the return movement thereof. 60

Figure 6 is an elevation of the type bar and guide.

Figure 7 is a similar view showing a modification.

The invention may be embodied in typewriting machines which differ widely in other respects and for this reason the other instrumentalities of the typewriting machine have not been illustrated. There is indicated the usual platen A which is movable 70 to a second position indicated in dotted lines by any usual or desired form of case shift mechanism.

Each type bar 1 is mounted to slide and is provided with four type a, b, c, and d. 75 When the platen is in its lower position as shown in Figure 1, and the type bar is given merely its longitudinal movement, it will print from the type b as shown in this figure. If the type bar is simultaneously lifted consequent upon the depression of the other key which controls the same, the imprint will be from the type d which is the lowest type of the other group. If it is desired to print from types a or c, the platen is shifted to the dotted line position and the two key levers control the selection of these types in similar manner. 85

Each type bar 1 slides on a supporting and guiding member 2 which is pivoted at 3 to a fixed part of the machine. As clearly shown in Figures 6 and 7 this guide member is formed with bent over parts 4 at the top and bottom which engage one face of the sliding type bar and has indent projections 5 which engage the other face of the type bar. At the same time bent over ears 6 on the guide member engage the upper and lower edges of the type bar. In the modification shown in Figure 7 instead of the indented portions 95 in the guide member 2, the indentations are formed in the type bar 1. 100

5 there are used pins 7 carried by the guide and engaging the face of the type bar.

Attached to an intermediate portion of the type bar at 8 is a link 9 which is illustrated 5 as being formed with two parallel members connected by web portions 10. This is convenient in manufacture and to add stability to the parts and is preferable since one of the guide members passes on each side of the type bar and serves to guide the rear end thereof in its movement. It is possible, however, to omit the web portion 10 and employ two separate parallel links or a single link member may be used.

15 Pivoted at 11 to the link 9 is one end of a short link 12 which together with the link 9 forms a toggle member. This link 12 is pivoted at 13 at its other end to a supporting member 14 mounted in the frame of the machine. An extension 15 from this member passes through a bar 16 carried by the machine frame into which bar is threaded a screw member 17 having an intermediate reduced portion 18 in which fits a lug 19 projecting from the extension 15. It is obvious that by means of the screw 17 the position of the supporting member 14 may be changed and the effective printing position of the type bar varied. A set screw 20 holds the parts 25 in adjusted position.

Pivoted at 21 to an ear of the link 12 is one end of a link 22 which is pivoted at its other end at 23 to a lever including a pair of arms 24, one arm of which passes on each 30 side of the support 14. This lever 24 is pivoted to the support 14 at 25 and one of the arms thereof is extended downwardly and forwardly at 26. The lower end of the extension is pivoted at 27 to an intermediate point 35 of a lever 28, one end of which is pivoted at 29 to a pawl carrier 30. The other end 31 of the lever 28 is connected by a spring 32 to a point 33 on the support 14 and this spring tends to return the parts to normal position. 40

45 The extension 26 has an offset ear 34 which is designed to contact with a resilient stop 35 at the end of the operative movements of the parts. This stop is carried by an extension 36 on the supporting member 14.

50 The pawl carrier 30 is loosely mounted on a constantly rotating power shaft 37 to which is rigidly fastened a ratchet wheel 38. Also loosely mounted on the shaft 37 is a member 39, one end of which is forked to engage a pin 40 eccentrically mounted on an adjustable member 41. The other end 42 of this member is provided with an inclined surface 43, the purpose of which will be hereinafter set forth.

55 Each type action is controlled by two key levers B and C which are pivoted in the usual manner at D. Upon depression of the key lever B, the type bar 1 will be moved forwardly to printing position but will not be raised, whereas upon depression of the key

lever C the type bar will be raised and moved forwardly to printing position. A trip lever 44 is pivoted at 45 in a frame member 46 and the upper end of this lever is connected by spring 47 to an angular member 48 fast to a frame portion 49. Intermediate its ends the lever 44 is provided with two elongated slots 50 and 51. A link 52 connects the key lever B to the slot 50 and a link 53 connects the key lever C to the slot 51 so that the lever 44 will be moved by the depression of either key lever without affecting the position of the other key lever. The key levers are normally returned to position by springs 54 attached at one end thereto and at the other end to a 70 plate 55 carried by the frame member 46.

The free end of the trip lever 44 is provided with a casing 56 adapted to contain a resilient or noiseless pad 57, the end of which may be enlarged. Pivoted to the pawl carrier 30 on an axis 58 is a pawl 59 having an engaging tooth 60, and a short arm 61 is also pivoted on the axis 58. A pin 62 on the pawl is connected to a pin 63 on the arm 61 by means of a spring 64 which, when the parts are in the normal position, lies in a straight line approximately passing through the axis of the pivot 58. At this time the pin 63 engages the under edge of a fixed frame member 65. The upper end of the pawl carrier 30 is provided with a sound deadening stop 66 and also with an ear 67. This pawl carrier is also provided with another ear 68 which, when the parts are in the Figure 1 position, engages the under side of the arm 61. This arm is, therefore, held at this time between the fixed member 65 and the ear 68 on the pawl carrier and cannot have any independent movement at this time.

Assuming that the parts are in the Figure 1 position and the key B is depressed, this will pull down on the link 52 and move the trip lever 44. The end 57 of this lever rests on top of the pawl at this time and this movement will swing the pawl about the axis 58 105 so that the tooth thereof will engage the ratchet wheel 38. The parts at this time are in the full line position of Figure 4. It will be seen that the arm 61 has not moved but that the spring 64 has moved to a position where 115 it lies below the axis 58. It will, therefore, hold the pawl in engagement with the ratchet wheel. Since the shaft 37 and the ratchet wheel 38 are constantly rotating in clockwise direction, the pawl will be given a movement 120 toward the dotted line position of Figure 4. When this position is reached the pin 63 engages the cam surface 43 of the member 42 and moves the arm 61 toward the Figure 5 position in which the spring 64 lies on the upper side of the axis 58. In this movement the pawl engages an offset ear 42' on the lever 39 which moves the pawl out of engagement with the ratchet, the latter part of the pawl movement being assisted by the spring 64. 130

Irrespective of whether or not the key lever B has been released, the pawl carrier and pawl together with all connected parts will immediately return to normal position. The dotted line position of Figure 5 shows an intermediate position of the pawl 59 and the arm 61 on this return movement. It will be noted that the pin 63 will come in contact with the fixed member 65 and the arm 61 cannot move any farther in that direction. The subsequent movement of the pawl carrier 30 will, therefore, give an independent movement of the arm 61 on the pivot 58 until the arm takes up the Figure 1 position. If the key lever has been released, the pawl will immediately swing under the end 57 of the trip lever 44, but if not, the end of the pawl will engage against the enlarged end 57 and the key lever may be released at any time thereafter to permit the trip lever 44 to move to its normal position, whereupon all parts will occupy the position shown in Figure 1.

If the key lever C is depressed, precisely the same action will take place but at this time the type bar will also be moved vertically through a tilting movement in order to print from the corresponding type of the lower group. This movement is attained in the following manner.

A lever 69 is pivoted to the frame member 49 to turn on the axis 3 and an ear 70 on said lever is connected by a spring 71 to an ear 72 on the type bar guide or carrier 2. The lower end of the lever 69 has a pin 74 projecting to one side thereof and a push rod 75 which is pivoted at one end at 76 to the lever 24 has its other end normally in position to engage the pin 74. This push rod 75 is connected by a link 77 to the key lever B so that when this lever is depressed the push rod 75 is moved out of engagement with the pin 74 to the dotted line position of Figure 1, and consequently said rod has an idle movement.

However, if the lever C is depressed, this will operate the trip lever 44 through the link 53 but will have no influence upon the push rod 75 so that when the type action is operated the movement of the lever 24 will actuate the push rod 75 and through the connections just described will rock the type guide 2 to the Figure 2 position. It is to be noted that the spring 71 is quite a strong spring but will permit continued movement of the push rod 75 after the type guide has reached the Figure 2 position. When the type guide is rocked to the Figure 2 position, it will be returned by means of a spring 78 connected to the member 48 and to an ear on the type guide.

From the foregoing, it will be observed that when it is desired to print from either type *a* or *b*, the key lever B will be depressed. During the depression of this key lever B, the push rod 75 will be swung downwardly

out of engagement with the pin 74 through the medium of the link 77. Simultaneously, the trip lever 44 will be swung downwardly through the medium of the link 52 and the pawl 59 will be moved into operative engagement with the ratchet wheel 38. The pawl carrier 30 will then be swung towards the right. This movement of the pawl carrier 30 moves the lever 28 downwardly therewith and as a result the lever 24 is rocked on its pivot 25. The movement of the lever 24, through the medium of the link 22 and the toggle connection 9, 12, causes the type bar 1 to be moved forwardly to printing position to print from the type *b* when the platen is in its lower case position or to print from the type *a* when the platen is in its upper case position. When the pawl 59 is released from the ratchet wheel 38, the spring 32 will function to return the pawl carrier 30, the lever 28, the lever 24, the link 22, toggle 9, 12, and the type bar 1 to their normal positions as shown in Figure 1.

When it is desired to print from either type *c* or *d*, the key lever C is depressed. Inasmuch as the push rod 75 is not connected with the key lever C, the depression of said key lever will not disengage the push rod from the pin 74. Consequently, when the key lever C is depressed the operating lever 24 will be swung, the push rod 75 will be moved to swing the lever 69 to raise the type bar, and the toggle 9, 12 will be actuated to slide the type bar to print. The type bar is raised through the lever 69 pulling the spring 71 which in turn rocks the pivoted support 2 until the eccentric stop 84 engages the stop screw 81. Thus the raised position of the type bar is predetermined by the setting of the eccentric stop 84 and the screw 81. The type bar reaches its raised position prior to the completion of the sliding or printing movement thereof, and although the toggle 9, 12 and the push rod 75 continue to move, the push rod will have no effect on the swinging support 2 because of the spring 71 which permits the lever 69 to be further rocked by the push rod. Thus, in this raised position of the type bar, the type *d* may be printed when the platen is in its lower position and the type *c* printed when the platen is in its upper position.

There is also illustrated means for silently stopping the rocking movement of the type guide. In the form shown in Figure 1 there is provided a U-shaped member 79 in which are threaded on opposite sides, adjustable stop screws 80 and 81. The type guide has an upwardly extending arm 82 to which is loosely pivoted at 83 a circular weight 84. The pivot 83 is eccentric so that the weight normally tends to occupy a certain position. When the parts are returned to normal position as shown in Figure 1, the screw 80 engages one side of the eccentric member 84 and swings it until

the point engaged reaches a dead center position. When the type guide is tilted, the opposite screw 81 engages the other side of the eccentric member 84 and swings it in the opposite direction to the position shown in Figure 2.

A modification of this construction is shown in Figure 3. There is here provided a trough like member 85 provided with a slotted cover 86 and the arm 82 from the type guide 2 projects upwardly through a slot into the chamber thus formed. This chamber has inclined sides 87 and balls 88 are placed therein on opposite sides of the arm 82 of the type guide. 10 Adjustable stop screws 89 and 90 are threaded into opposite sides of the member 85 and when the type carrier is rocked, it will engage one or the other of the balls 88 and roll the same up the incline until it contacts with the 15 proper stop screw 89 or 90.

It will be noted that while the fundamental idea is similar, to that disclosed in my prior application, nevertheless quite radical changes have been made in the direction of simplifying the construction and increasing the efficiency of the operation of the device. It is also apparent that other changes may be made in the detail construction without in any way departing from the spirit of the invention, which is to be regarded as limited only by the scope of the appended claims.

I claim as my invention:

1. A type action comprising a slidable type bar provided with a plurality of groups of type, key levers associated with the type bar and corresponding in number to the number of groups, a movable support for the type bar, power operated means controlled by the depression of each key lever for moving the 35 type bar to the printing point, and mechanism normally in position to be actuated by said power operated means for moving said support.

2. A type action comprising a slidable type bar provided with a plurality of groups of type, key levers associated with the type bar and corresponding in number to the number of groups, a movable support for the type bar, power operated means controlled by the depression of each key lever for moving the type bar to the printing point, mechanism normally in position to be actuated by said power operated means for moving said support, and means controlled by one key lever for rendering said mechanism inoperative.

3. A type action comprising a slidable type bar provided with a plurality of groups of type, key levers associated with the type bar and corresponding in number to the number of groups, a pivoted support for the type bar, power operated means controlled by the depression of each key lever for moving the type bar to the printing point, and normally operative connections between said power op-

erated means and the support for tilting the latter.

4. A type action comprising a slidable type bar provided with a plurality of groups of type, key levers associated with the type bar and corresponding in number to the number of groups, a pivoted support for the type bar, power operated means controlled by the depression of each key lever for moving the type bar to the printing point, normally operative connections between said power operated means and the support for tilting the latter, and means controlled by one key lever for breaking said connections.

5. A type action comprising a slidable type bar provided with a plurality of groups of type, key levers associated with the type bar and corresponding in number to the number of groups, a pivoted support for the type bar, power operated means controlled by the depression of each key lever for moving the type bar to the printing point, and normally operative connections between said power operated means and the support which include a pivoted lever yieldingly connected to the support.

6. A type action comprising a slidable type bar provided with a plurality of groups of type, key levers associated with the type bar and corresponding in number to the number of groups, a pivoted support for the type bar, power operated means controlled by the depression of each key lever for moving the type bar to the printing point, normally operative connections between the power operated means and the support which include a pivoted lever yieldingly connected to the support, and means controlled by one key lever for breaking said connections.

7. A type action comprising a slidable type bar provided with a plurality of groups of type, key levers associated with the type bar and corresponding in number to the number of groups, a movable support for the type bar, power operated means operative upon the depression of one of said key levers for moving the type bar to the printing point and for moving said support to select a different group, and means including elements having a rolling contact for silently limiting the movement of said support.

8. Power driving means for type bar actions comprising a constantly rotating shaft, a ratchet wheel thereon, a pawl carrier loosely mounted on said shaft, a pawl on said carrier, key operated means for moving said pawl into engagement with the ratchet so that the carrier will rotate with the shaft, and a spring which holds the pawl in either operative or inoperative position.

9. Power driving means for type bar actions comprising a constantly rotating shaft, a ratchet wheel thereon, a pawl carrier loosely mounted on the shaft, a pawl pivoted to the carrier, an arm also pivoted to the carrier on

the same axis as the pawl, a spring connecting the pawl and arm and normally holding the pawl out of engagement with the ratchet, and key operated means for moving the pawl independently of the arm into engagement with the ratchet wheel, the spring then lying on one side of the axis of the pawl and arm and tending to hold the pawl in engagement with the ratchet.

10. Power driving means for type bar actions comprising a constantly rotating shaft, a ratchet wheel thereon, a pawl carrier loosely mounted on the shaft, a pawl pivoted to the carrier, an arm also pivoted to the carrier on the same axis as the pawl, a spring connecting the pawl and arm and normally holding the pawl out of engagement with the ratchet, key operated means for moving the pawl independently of the arm into engagement with the ratchet wheel, the spring then lying on one side of the axis of the pawl and arm and tending to hold the pawl in engagement with the ratchet, and means operative during the rotation of the pawl carrier for moving the arm to bring the spring to the other side of the axis.

11. Power driving means for type bar actions comprising a constantly rotating shaft, a ratchet wheel thereon, a pawl carrier loosely mounted on the shaft, a pawl pivoted to the carrier, an arm also pivoted to the carrier on the same axis as the pawl, a spring connecting the pawl and arm and normally holding the pawl out of engagement with the ratchet, key operated means for moving the pawl independently of the arm into engagement with the ratchet wheel, the spring then lying on one side of the axis of the pawl and arm and tending to hold the pawl in engagement with the ratchet, and fixed means engaged by the arm during the rotation of the pawl carrier to move the arm independently of the pawl to bring the spring to the other side of the axis.

12. Power driving means for type bar actions comprising a constantly rotating shaft, a ratchet wheel thereon, a pawl carrier loosely mounted on the shaft, a pawl pivoted to the carrier, an arm also pivoted to the carrier on the same axis as the pawl, a spring connecting the pawl and arm and normally holding the pawl out of engagement with the ratchet, key operated means for moving the pawl independently of the arm into engagement with the ratchet wheel, the spring then lying on one side of the axis of the pawl and arm and tending to hold the pawl in engagement with the ratchet, a fixed stop for limiting the movement of the arm in one direction, and a stop on the carrier for limiting its movement in the other direction.

13. A type action comprising a type bar mounted for sliding and tilting movements, two key levers associated with said type bar, a movable support for the type bar, a con-

stantly rotating shaft, a ratchet wheel fixed to the shaft, a pawl carrier loosely mounted on said shaft, a pawl on said carrier, connections including a lever between the pawl carrier and the type bar for moving the latter to printing position upon engagement of the pawl with the ratchet wheel, means for moving said pawl into engagement with the ratchet wheel upon depression of either key lever, a lever and connections between the lever and the type bar support for tilting the support upon movement of the lever, a push rod pivotally connected to the lever of the type bar moving means and normally engaged with the support tilting lever whereby upon depression of one key lever the type bar will be moved to printing position and the support tilted, and a connection between the push rod and the other key lever whereby upon depression of said other key lever the push rod will be disengaged from the support tilting lever and the type bar moved to printing position without tilting said support.

14. A type action comprising a type bar mounted for sliding and tilting movements, two key levers associated with said type bar, a movable support for the type bar, a constantly rotating shaft, a ratchet wheel fixed to the shaft, a pawl carrier loosely mounted on said shaft, a pawl on said carrier, yieldable means for normally holding the pawl out of engagement with the ratchet wheel, means for sliding the type bar to printing position including a lever, a link connecting the lever and the pawl carrier, a trip lever, and loose connections between the trip lever and both key levers whereby either key lever during depression thereof will move the trip lever into engagement with the pawl and thereby move the latter into engagement with the ratchet wheel, a lever and connections between the lever and the type bar support for tilting said support upon movement of the lever, a push rod pivotally connected to the lever of the type bar sliding means and normally engaged with the support tilting lever whereby upon depression of one key lever the type bar will be moved to printing position and the support tilted, and a connection between the push rod and the other key lever whereby upon depression of said other key lever the push rod will be disengaged from the support tilting lever and the type bar moved to printing position without moving said support.

15. In a typewriting machine, the combination with a type bar support mounted to swing about a fixed axis, of a type bar slidably mounted on said support, and means for swinging the support and sliding the type bar including an operating lever, a lever fulcrumed on the fixed axis of the type bar support, a spring connecting the last mentioned lever and the support, a stop

means for limiting the upward swinging movement of the type bar support, a push rod operatively connected between the levers, connections between the operating lever and the type bar for sliding the latter, and key controlled means for actuating the operating lever.

16. In a typewriting machine, the combination with a type bar support mounted to swing about a fixed axis, of a type bar slidably mounted on said support, and means for swinging the support and sliding the type bar including an operating lever, a lever fulcrumed on the fixed axis of the type bar support, a spring connecting the last mentioned lever and the support, a stop means for limiting the upward swinging movement of the type bar support, a push rod operatively connected between the levers, connections between the operating lever and the type bar for sliding the latter, power means normally disconnected from the operating lever, and a key lever adapted upon depression thereof to connect the power means with the operating lever.

In testimony whereof, I have hereunto subscribed my name.

WILLIAM O. MICHELS
